ATTORNEY

UNITED STATES PATENT OFFICE.

ALBERT DAVIGNON, OF CHISWICK, ENGLAND, ASSIGNOR TO WITCOMBE, McGEACHIN & CO., OF NEW YORK, N. Y., A PARTNERSHIP COMPOSED OF H. A. WITCOMBE AND GEORGE McGEACHIN.

DESIGN FOR FABRIC, WALL PAPER, WRAPPING PAPER, OR SIMILAR ARTICLE.

60,647.

Specification for Design.

Patented Mar. 21, 1922.

Application filed August 31, 1921. Serial No. 497,393. Term of patent 7 years.

To all whom it may concern:

Be it known that I, ALBERT DAVIGNON, a citizen of France, residing at Chiswick, county of Middlesex, England, have invented a new, original, and ornamental Design for Fabric, Wall Paper, Wrapping Paper, or Similar Article, of which the following is a specification, reference being had to the accompanying drawing, forming part thereof.

The figure is a plan view of a portion of a printed fabric showing an embodiment of my new design.

I claim—

The ornamental design for fabric, wall paper, wrapping paper, or similar article, substantially as shown.

A. DAVIGNON.
